UNITED STATES PATENT OFFICE.

GREGOR MACMILLAN, OF OTTAWA, ONTARIO, CANADA.

INTERCHANGEABLE LOCKING TAB.

Application filed January 30, 1923. Serial No. 615,792.

To all whom it may concern:

Be it known that I, GREGOR MACMILLAN, a citizen of Dominion of Canada, and resident of Ottawa, in the county of Carleton 5 and Province of Ontario, Dominion of Canada, have invented certain new and useful Improvements in Interchangeable Locking Tabs, of which the following is a specification.

10 This invention relates to improvements in interchangeable lock tabs and more particularly tabs used in all forms of file containers, including folders, pockets, binders and the like forming an essential feature in 15 up to date office equipment.

A further object of the invention resides in the provision of an adjustable and interchangeable reinforced indexing tab of the character stated, that can be quickly and 20 securely attached and which, when attached, can not be displaced in the ordinary handling of the files.

Another object of the invention resides in the provision of an efficient and economical 25 markable indexing tab without any protruding parts or points to interfere with the filing of the member to which it is attached.

The invention has for a further object the provision of a tab of the class stated with a 30 double face or side index to fit over both sides of the back or front portion of a file or a container to prevent the papers when filed from being intercepted between the wall of the container and the tab.

35 A still further object of the invention resides in the provision of a tab of the character stated which may be used and indexed more than once by reversing it.

The invention has for a still further object 40 the provision of a tab of the character set forth and consists essentially of a strip of suitable material slotted toward one end and formed with a tongue at the other end designed to engage the slotted end to lock 45 the tab in folded position on a file or the like.

With the foregoing and other objects in view as will appear as the description proceeds, the invention consists in the novel construction, combination and arrangement 50 of co-operating elements as hereinafter more specifically set forth, claimed and shown in the accompanying drawings forming a part of the present application, in which:

Fig. 1 is a perspective view of the folder

with three different forms of the tab there- 55 on.

Fig. 2 is a similar view of the folder, closed.

Fig. 3 is an enlarged detail section substantially on the plane of line 3—3 of Fig. 2. 60

Fig. 4 is an enlarged sectional view substantially on the plane of line 4—4 of Fig. 2.

Fig. 5 is a plan view of the tab in open position.

Fig. 6 is a plan view of the tab in closed 65 position.

Fig. 7 is a plan view of the tab in closed position and showing the rear side thereof.

Fig. 8 is a central vertical section of the tab in use. 70

Fig. 9 is a section on the plane of line 9—9 of Fig. 7.

Fig. 10 is a plan view of the blank used for a progress tab.

Fig. 11 is a plan view of the filing tab, 75 open.

Fig. 12 is a sectional view through the tab shown in Fig. 11.

Fig. 13 is an enlarged section, showing 80 the tab in closed position.

Fig. 14 is a perspective view of the filing tab showing a portion thereof folded to clearly illustrate the location of the folding crease.

Fig. 15 is a plan of a modified form of 85 the tab, showing the same in open position.

Fig. 16 is a plan of the tab disclosed in Fig. 15 and showing the tab in closed position.

Fig. 17 is a plan of a further modified 90 form of the tab in open position.

Fig. 18 is a plan of the tab disclosed in Fig. 17 and showing the tab in closed position.

Fig. 19 is a plan of a further modified 95 form of tab in open position.

Fig. 20 is a plan of the tab disclosed in Fig. 19 and showing the same in closed position.

Fig. 21 is a plan of a still further modified form of tab, showing the same in open 100 position.

Fig. 22 is a plan of the tab disclosed in Fig. 21 and showing the same in closed position.

Referring more in detail to the drawings in which similar reference characters designate corresponding parts throughout the 105

several views, a folder or container A, of any well-known type may be provided along one edge with a series of spaced slots B therein to receive the tab C forming the subject matter of the present invention.

The tab C may be constructed of strong fibrous card or other suitable material and includes a strip 10 folded to fit on the folder or file container A, the strip 10 being rounded at one end and provided adjacent thereto with the transverse arcuate slot 11, Figs. 5, 6, designed to register with the slots B in the folder. The other end of the strip 10 is suitably cut and reduced to form a tongue 12 with slots 13 on each side thereof in the face of the strip 10 and providing on either side of the tongue 12 the fingers 17 having rounded free ends and the purpose of which will later appear.

By elongating the tab, as shown in Fig. 10 and indicated by the numeral 10^x, the same is made applicable to files, folders, containers and the like in the form of a progressive tab as illustrated in Figs. 1 to 4 and 11 to 15, inclusive. The tab per se is formed of a strip of material 10^x provided with an integral tongue 12, which is adapted to engage in the slot 11 formed in the other end of the tab. As clearly shown in Figs. 1 and 13, the body of the tab may be bent upon itself, and for this purpose is provided with creases as at 15^a, and if desired, may be secured in such position by the clip 15^b which extends through said tongue and the opening 15^a as shown in Fig. 13.

In Figs. 15 and 16 another form of the tab is disclosed with a bifurcated tongue 12^a which is tapered and provided at the free ends of the sections thereof with outwardly turned and rounded locking extensions 12^b. The slot 11^a is also practically straight with the ends thereof turned, so that the sections of the tongue 12^a will lock to better advantage in the folded body 10 of the tab after being extended through the slot 11^a. The complete tab C is substantially the same in construction as the previous forms.

The modified form of tab C disclosed in Figs. 17 and 18 comprises a body 10 having the tongue 12^c extended from one end and carrying on one side of its free end the locking extension 12^d. The arcuate slot 11^c is formed in the other end portion of the body 10 and extended at an oblique angle, so as to permit ready insertion of the tongue 12^c and secure locking of this tongue in the folded-over body of the tab, as shown in Fig. 18.

The form disclosed in Figs. 19 and 20 includes the body 10^e having a tapered tongue 12^e with a rounded free end, the same as the forms disclosed in Figs. 5 and 9 inclusive. The slot 11^e also corresponds

to the slot 11 in the forms 5 to 9 inclusive. This form disclosed in Figs. 19 and 20 is especially designed for forms produced from light sheet-metal and is provided with an open window face 18 to expose therein 70 an indexing card 19 inserted from the end and held in position between the walls of the tab by punched-out tongues 16 designed to prevent the card from slipping out of position. This form of tab is more especially intended for the heavier classes of material, such as pressed board and steel guides etc.

The form of tab J disclosed in Figs. 21 and 22 includes a body 10^h which is provided with a slot 11^f extended transversely in the upper end portion and having a right angle extension 11^g opening upon the end of the body 10^h. The corner portions 10^a of the body are cut at an angle, as shown clearly in Fig. 21 and the body is adapted to be folded upon itself intermediate its ends as shown by the dotted line 10^b, suitable notches 10^c being provided in the side edges of the body 10^h at the ends of the dotted line 10^b. The tongue 12^f is extended from the other end of the body 10^h and part of the central portion 12^g of the tongue 12^f is tapered on its opposite sides to provide the reduced portion or neck 12^h adjacent the end or head 12ⁱ of the tongue 12^f. The free end of the head 12ⁱ is rounded, so that the tongue 12^f may be readily secured in locked position within the slot 11^f. A main or inner portion of the tongue 12^f is tapered and separated at its sides from the end of the tab body 10^h by slits 13^f, thereby providing tapered fingers 17^f which may grip the end of the folder or other member to which the tab is attached, the same as in the other forms of tab. It may also be stated at this time that the fingers 17^f correspond to the fingers 17 included in the forms disclosed in Figs. 5 to 9 inclusive and Figs. 15 to 20 inclusive, except that they lie close to the tongue 12^f, while material is cut away from between the tongue and the fingers in the other forms mentioned. In the forms disclosed in Figs. 1 to 4 inclusive and 10 to 14 inclusive, the fingers are dispensed with and the tongue is of substantially the same width throughout its length.

It is believed the complete construction and operation of the tab may now be apparent from the foregoing paragraphs taken in connection with the accompanying drawings without further detail description. It may be mentioned, however, that a tab as shown in Figs. 1 to 9 inclusive, and as far as the principal construction is concerned, as shown in all of the figures, is folded to fit the slotted side of the member to which it is to be attached, the tongue 12 being inserted through this slot and bent upwardly to engage with the slot in the tab to be locked therein between the inner face of the tab 130

and the member to which the tab is attached.

To remove the tab it only necessary to release the tongue and then withdraw the complete tab from the member. This applies to each form of the tab disclosed in the application.

While the preferred embodiments of the invention have been disclosed it is to be understood that minor changes in the details of construction, combination and arrangement of co-operating elements may be resorted to within the scope of what is claimed without departing from the spirit of the invention.

What I claim as new is:

1. A tab for filing folders, containers and the like; comprising a strip of suitable material provided with an arcuate slot adjacent to one end; said strip being formed with a locking tongue at the other end designed to embrace the slotted end and to extend therein to lock the tab in folded position on a filing folder, container or the like; said tab having slits in the face thereof on each side of the tongue to provide fingers adapted to grip the edge of the folder, container or the like to which the tab is applied.
2. The combination with a file element having slots therein; of a foldable tab designed to embrace the same; one end of the tab having a slot designed to register with the slots in the file element; the other end of the tab being formed with a tongue adapted to extend through the element slot and into the tab slot to lock the tab on the file element; gripping means on the tab designed to engage the edge of the file element; and locking means formed on said tongue.
3. A tab of the character described comprising a strip of material slotted at one end and formed with a tongue at the opposite end designed to engage the slotted end to lock the tab on a file container.

4. In a device of the character described; the combination with a filing device having a plurality of slots formed therein; of an interchangeable locking tab comprising a slotted strip of material designed to embrace the sides of the filing device and formed with the locking tongue adapted to extend through any one of the slots in the filing device and through the tab slot, whereby the tab is locked on the filing device.

5. The combination with a tab; of a member to which said tab is to be secured; said member being formed with a plurality of spaced slots; said tab having a slot and a locking tongue; said locking tongue being designed to extend through any one of the slots of the member and into the slot of the tab to lock the tab on said member.

6. A tab of the character described comprising a strip of material slotted at one end and formed with a tongue at the opposite end designed to engage the slotted end to lock the tab on a file container; said tongue being tapered toward its free end; and a pair of fingers extended normally in parallel relation to said tongue.

7. The combination with a tab; of a member to which said tab is to be secured; said member being formed with a plurality of spaced slots; said tab having a slot and a locking tongue; said locking tongue being designed to extend through one of the slots of the member and into the slot of the tab to lock the tab on said member; said tongue being bifurcated with the free ends of the separated portions thereof turned outwardly to form locking extensions; the slot provided in the tab to receive the tongue having its ends turned to assure firm locking of the tongue within the slot; and a pair of fingers extended from said tab on opposite sides of the tongue.

In testimony whereof, I affix my signature.

GREGOR MacMILLAN.
